UNITED STATES PATENT OFFICE.

EDWARD CLYDE HONEA, OF ALEXANDRIA, LOUISIANA.

FLANGE-TURNER.

1,211,155.

Specification of Letters Patent. Patented Jan. 2, 1917.

Application filed March 4, 1916. Serial No. 82,195.

To all whom it may concern:

Be it known that I, EDWARD CLYDE HONEA, a citizen of the United States, residing at Alexandria, in the parish of Rapides and State of Louisiana, have invented certain new and useful Improvements in Flange-Turners, of which the following is a specification.

My invention relates to a device for turning the flanges of wheels on railway vehicles, such as locomotives, cars, and the like, and has particular reference to a device adapted to be secured to a brake shoe head in the place ordinarily occupied by the brake shoe and to be held into proper contact with the flange of the wheel by a suitable application of the brakes, for cutting or turning the flange upon the movement of the vehicle in the proper direction.

An important object of the invention is to provide a device of the above mentioned character, which is simple in construction, inexpensive to manufacture, convenient in use, and highly efficient in operation.

Other objects and advantages of the invention will be apparent during the course of the following description.

In the accompanying drawings forming a part of this specification and in which like numerals are employed to designate like parts throughout the same, Figure 1 is a side elevation of a device embodying my invention, showing the same applied to a brake shoe head, Fig. 2 is an edge elevation of the same removed, Fig. 3 is an end elevation of the same, showing the cutter, Fig. 4 is a plan view of the same, and, Fig. 5 is a transverse sectional view taken on line 5—5 of Fig. 4.

In the drawings, wherein for the purpose of illustration is shown a preferred embodiment of my invention, the numeral 10 designates a flanged wheel, which for the purpose of illustration, will be shown as one of the drivers of a locomotive, while it is to be understood that the invention is adapted for acting upon the flanged wheels of any railway vehicle. Arranged upon one side of the wheel 10 is a brake mechanism, of any well known or preferred construction, comprising a brake shoe head 11, supported by a pivoted link 12. As the brake mechanism forms no part of the present invention, no further description thereof is thought to be necessary.

My device comprises a longitudinally

curved body portion 13, adapted to be arranged upon the face of the brake shoe head 11, in place of the brake shoe, which has been removed. Any suitable means may be employed to retain the body portion 13 upon the head 11. For the purpose of illustration I have shown the body portion 13 as provided near its upper end with a lip or projection 14, adapted to enter an opening 15 formed in the head 11. The body portion 13 is provided at its lower end with a flange 15, to be arranged beneath the lower end of the head 11. The body portion 13 has a transverse opening 16 for receiving a screw 17 or the like, serving to attach the body portion 13 to the head 11, the head of the screw being counter-sunk, as shown.

The body portion 13 is provided at its inner edge with a longitudinally extending groove 18 formed in a longitudinal head 18', for receiving the flange 19' of the wheel. Arranged upon the upper end or top of the body portion 13 is a cutter 19, pivoted thereto as shown at 20. This cutter has its cutting edge 21 of a proper curvature, to impart to the flange the desired shape. The cutting edge 21 is adapted to be moved across the groove 18, to contact with the flange 19' by the adjusting of a bolt 22, having screw-threaded engagement within an apertured extension 23, rigidly secured to the edge of the body portion 13, at its upper end. The bolt 22 contacts with the extension of the cutter 19, as more clearly illustrated in Fig. 3.

In the use of the device, the body portion 13 is secured to the head 11, in the place normally occupied by the brake shoe, and this body portion is secured thereto, as above indicated. The brakes are properly applied to bring the body portion 13 into contact with the periphery of the wheel, but not sufficiently to prevent the travel of the vehicle. By means of a wrench or the like, the adjusting bolt 22 may be manipulated to adjust the cutter 19, so that its cutting edge 21 will properly cut or turn the flange 19'. The vehicle is then caused to travel in the proper direction for causing the cutter 21 to act upon the flange, and turn the same to the proper shape. It is obvious that the device may be constructed for use upon the right or left wheels of the vehicle.

It is to be understood that the form of my

invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

10. 1. A device for turning the flanges of wheels, comprising a body portion adapted to be secured to a brake shoe head, a transverse cutter pivotally connected with the body portion and adapted to contact with the periphery of the flange to turn it, and means to swing the cutter upon its pivot and hold it in adjustment at the desired position.
20. 2. A device for turning the flanges of wheels, comprising a body portion having a groove to receive the flange, and a transverse cutter pivoted upon the body portion

and adapted to be moved across the groove to contact with the periphery of the flange.

3. A device for turning the flanges of 25 wheels, comprising a body portion adapted to be secured to a brake shoe head and provided upon one longitudinal edge with a head having a groove to receive the flange of the wheel, a cutter extending transversely 30 of the body portion at one end thereof and having its cutting end adapted for movement across the groove, a bolt pivotally connecting the cutter and body portion, and an adjusting bolt having screw-threaded engagement with a portion of the body portion and contacting with one end of the cutter to swing it upon its pivot.

In testimony whereof I affix my signature in presence of two witnesses.

EDD CLYDE HONEA.
